SYRINGE

Roger D. Barr, P.O. Box 3741, Baytown, Tex.

Filed June 17, 1963, Ser. No. 75,393

Term of patent 14 years

(Cl. D83—12)

FIG. 1 is an elevation of a syringe with the plunger in an extended position, showing my new design;

FIG. 2 is an elevation thereof, rotated 90° with the plunger shown in closed position; and

FIG. 3 is a top plan view thereof.

The undisclosed sides of the plunger are substantially the same as the side shown in FIG. 1.

I claim:

The ornamental design for a syringe, as shown and described.
